PADLOCK

James A. Cox, Santa Fe, N. Mex.

Application March 1, 1937, Serial No. 128,537

2 Claims. (Cl. 70—38)

This invention relates to padlocks and has for the primary object the provision of a device of this character which will exclude rain to prevent the movable parts within the lock body from 5 rusting and becoming inoperative or to prevent the accumulation of water therein to freeze in cold weather and interfere with the operation of the movable parts.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a vertical sectional view illustrating a padlock constructed in accordance with my invention.

Figure 2 is a sectional view taken on the line 2—2 of Figure 1.

Figure 3 is a sectional view taken on the line 3—3 of Figure 1.

Figure 4 is a sectional view taken on the line 25 4—4 of Figure 1.

Figure 5 is a plan view illustrating a key for operating the padlock.

Referring in detail to the drawing, the numeral 1 indicates the padlock outer shell or body, the same being of substantially rectangular longitudinal and transverse section, and having a chamber 2 opening through the bottom. The body 1 has a recess 4 disposed laterally of and communicating with the chamber 2 and located 30 in the lower portion of the body. A passage 5 is formed in the body and extends from the top of the body to the recess 4 to receive a shackle 6.

The shackle 6 includes leg portions 7 and 8 and the leg portion 8 is of a greater length than 40 the leg portion 7 and is received in the passage 5 and enters the recess 4' while the leg portion 7 may move into and out of a notch or recess 9 formed in the top wall of the body. The leg 7 of the shackle 6 when moved out of the recess 45 9 permits the shackle to be readily adapted to a keeper. The leg portion 8 of the shackle is free to slide in the passage 5 and also rotate. However, the leg portion 8 has a comparatively tight fit with the walls of the passage 5 to exclude 50 moisture, rain or the like from the recess 4'.

A block or support 10 is mounted in the chamber 2 and has formed therein a key opening or passage 11, one end of which opens through the bottom of the support. The support is provided 55 at the bottom with a flange 4 which fits snugly

against the bottom edge of the shell or body 1 to prevent entry of water into the chamber 2, in the body. Rivets or other connectors 12 are passed through the body 1 and support 10 to rigidly secure the parts together. Formed on 5 the support 10 are guides 13 and 14 and which are arranged at right angles to each other. A locking bolt 15 is slidably supported by the guide 13 and the guide 14 slidably supports a member 16 which parallels the leg portion 8 of the shackle 10 and is connected thereto by a link 17. The leg portion 8 of the shackle is acted upon by the spring 18 and the member 16 is acted upon by a spring 19. The springs 18 and 19 urge the leg portion 8 of the shackle 6 and the members 15 20 in the same direction. The spring acting on the leg portion 8 of the shackle disengages the leg portion 7 from the recess 9. A spring 20 acts on the locking bolt 15 to urge the same in a position to overlie the member 16 and to 25 retain said member against movement under the influence of the spring 19. The member 16 being held in the position stated by the locking bolt holds the shackle 6 or the leg portion 8 from movement under the action of the spring 25 18 and with the leg portion 7 extending into the recess 9.

Formed in the support 10 is a chamber 21 in which is pivotally mounted a series of superimposed tumblers 22 each having a slot 23 in one 30 end and a key slot 24 partially surrounded by a shoulder 25. The slots 23 open outwardly to the ends of the tumblers and are provided with branches 26. A pin 27 is secured to the locking bolt and extends through the slots 23 and when 35 the locking bolt overlies the member 16 the pin occupies the branches 26 preventing the locking bolt from being retracted from engagement with the member 16, consequently securing the shackle 6 against being moved to a released or unlocked 40 position. Leaf springs 28 act on the tumblers to position them so that the pin 27 enters the branches 26 of the slots 23. The locking bolt has a key opening 29 and located adjacent thereto is a shoulder 30. A key 31 is provided for actuating the tumblers so as to position said tumblers with the pin 27 lying in the slots and out of the branches. The key 31 also extends through the key opening 29 of the locking bolt whereby the same may be retracted against the action of the 50 spring 30 by the rotation of the key. The key has projections or bits for the actuation of the tumblers and the sliding bolt by engaging the shoulders 25 and 30. Thus it will be seen that this padlock is simple to actuate by a key and 55

when locked it will effectively prevent the shackle from being moved into an open position. Further, it is to be noted that the construction of the body and the connection of the shackle thereto is such that water and moisture will be excluded from the working parts inside of the body either when the shackle is open or closed.

What is claimed is:

1. A padlock comprising a body having a chamber and a passage communicating with said chamber and opening outwardly through a face of the body, said body having a recess, a shackle including leg portions, with one of said leg portions entering the chamber by way of said passage and the other leg portion adapted to be moved into and out of the recess by sliding and rotating said shackle, a member slidible in the chamber, means connecting said member to the shackle, spring means acting on said shackle and member, a support in said chamber and having a key passage to receive a key, a locking bolt slidible in said chamber to engage said member for securing the shackle in a locked position and having a key opening, a spring acting on said locking bolt, and tumblers carried by said support and connected with the locking bolt.
2. A padlock comprising a body having a chamber and a passage communicating with said

chamber and opening outwardly through a face of the body, said body having a recess, a shackle including leg portions, with one of said leg portions entering the chamber by way of said passage and the other leg portion adapted to be moved into and out of the recess by sliding and rotating said shackle, a member slidible in the chamber, means connecting said member to the shackle, spring means acting on said shackle and member, a support in said chamber and having a key passage to receive a key, a locking bolt slidible in said chamber to engage said member for securing the shackle in a locked position and having a key opening, a spring acting on said locking bolt, tumblers pivotally mounted on said support and having slots provided with branches, a pin secured to the locking bolt and extending into said slots, springs acting on said tumblers to position the latter to receive the pins in the branches of said slots, said tumblers having key openings to receive the key whereby the tumblers may be actuated by said key and the bolt slid by the rotation of the key with the pin moving in the slots of the tumblers to free the member connected to the shackle and permit said shackle to move into unlocked position.
